ABSTRACT OF THE DISCLOSURE

A vehicle and means, such as rails for guiding the vehicle along a straight path. The vehicle is transported back and forth between the ends of the path. The vehicle has a retractable mechanism for exerting an adjustable downward force as the vehicle moves. During test of radial strength, a boat fender is located under the lowered force-exerting mechanism, thereby rolling back and forth with the vehicle, while being subjected to a deforming force.

Background of the invention

This invention relates to boat fenders and, more particularly, to apparatus for testing the strength characteristics of boat fenders.

For many years cocoa and rope mats, pieces of cork, and solid nonporous rubber have served as boat fenders. These structures have proved useful to reduce or eliminate damage upon collision of two boats or a boat with a dock by absorbing the impact in part and distributing it over a larger area, but they suffer from numerous shortcomings. For the most part, these fenders absorb water, and nonbuoyant and subject to fast wear, and lack the ruggedness and resilience to withstand for extended periods of time the tremendous impacts that are encountered in normal use.

Recently a boat fender structure has been developed that overcomes these shortcomings to a large extent. This structure comprises a hollow, rubber core around which sheets of buoyant resilient material are wound in the form of a spiral and cemented together. The resulting cylindrical body is bagged, so to speak, in a snug-fitting, watertight cover. Fixtures mounted at either end of the structure are connected by a steel cable running through the hollow interior of the core. In use, these fenders are draped over the hull of the boat by lines secured to the fixtures. This fender structure has found wide acceptance because it is watertight, buoyant, rugged, and resilient. In addition, it is fire-resistant and easy to clean and repair.

Purchasers of the cylindrical boat fenders, notably the United States Navy, have prescribed certain procedures for testing the strength characteristics of a few samples from each lot of boat fenders manufactured. The selected samples must be able to withstand a minimum downward force exerted on its cylindrical surface as the fender rolls along the ground or other surface without splitting open. As the fender rolls, the downward force deforms it in a continually changing radial plane thereof. After this test, the axial strength of the fender is tested by pulling one of the fixtures. In order to pass the latter test, the fender must be able to withstand a minimum axial force without having the fixture pull loose.

Summary of the invention

According to the invention, a vehicle is provided that is restrained to move along a substantially straight path. Most advantageously, the vehicle rides on rails. The vehicle is transported continuously back and forth between the ends of the path. The vehicle has a retractable mechanism for exerting an adjustable downward force as it

2

moves back and forth. During test of the radial strength, the boat fender is located under the lowered force-exerting mechanism and rolls along the ground or other surface as the vehicle moves back and forth. To test the axial strength of the fender, the vehicle is simply stopped and the fender is retained by the lowered mechanism while the fixture is pulled.

Brief description of the drawing

The features of a specific embodiment of the invention are illustrated in the drawing, in which:

FIG. 1 is a side elevation view of apparatus for testing boat fenders; and

FIG. 2 is a front elevation view of the apparatus of FIG. 1.

Description of a specific embodiment

In the drawing, a vehicle 1 rides on parallel rails 2a and 2b that serve to guide vehicle 1 along a straight path. Vehicle 1 has wheels 4a and 5a in engagement with rail 2a and wheels 4b and 5b in engagement with rail 2b. Wheels 4a, 4b, 5a, and 5b are rotatably supported by yokes 6a, 6b, 7a, and 7b, respectively, on which vertical support members 8a, 8b, 9a, and 9b, respectively, rest. Arms 10 and 11 extend horizontally from the top of vertical support members 8a and 9a, respectively. As explained in detail below, arms 10 and 11 actuate switches that control the movement of vehicle 1 on rails 2a and 2b. Horizontal support members 12a and 13a run along the length of vehicle 1 between vertical support members 8a and 9a, while horizontal support members 12b and 13b run along the length of vehicle 1 between vertical support members 8b and 9b. Similarly, horizontal members 14 and 15 run along the width of vehicle 1 between vertical members 8a and 8b, and horizontal support members 16 and 17 run along the width of vehicle 1 between vertical support members 9a and 9b.

A horizontal platform 20 is located between vertical support members 8a, 8b, 9a, and 9b. The vertically oriented, movable arms of air cylinders 21a, 21b, 22a, and 22b are attached to platform 20 at its four corners. Air cylinders 21a and 21b are attached to horizontal support member 14 by brackets 23a and 23b, respectively. Similarly, air cylinders 22a and 22b are attached to horizontal support member 16 by brackets 24a and 24b, respectively. A heavy body 25, which could, for example, comprise a pile of bricks, rests on platform 20. Body 25 weighs more than the downward force to be exerted on the boat fender under test. At its ends, platform 20 has extensions 26a, 26b, 27a, and 27b, which are parallel to horizontal support members 15 and 17. Two cylindrical guides, such as those designated 28 and 29 in FIG. 1, are attached to each end of platform 20 with their axes parallel to horizontal support members 12 and 13. These guides glide along the respective vertical support members (8a, 8b, 9a, and 9b) as platform 20 is raised and lowered, thereby serving with extensions 26a, 26b, 27a, and 27b to prevent lateral motion of platform 20.

Before a boat fender is to be tested, platform 20 is first raised or retracted by actuating air cylinders 21a, 21b, 22a, and 22b. Then a boat fender, designated 35 in the drawing, is placed under platform 20, which is then lowered by releasing air cylinders 21a, 21b, 22a, and 22b, until boat fender 35 becomes deformed. The limit on the downward excursion of platform 20, and therefore the fraction of the weight of body 25 actually exerted on fender 35, is controlled by threaded stops such as those designated 36 and 37 in FIG. 1. These stops extend vertically through threaded holes in wheel yokes 6a, 6b, 7a, and 7b. When platform 20 is lowered, it moves downward until it comes to rest on the threaded stops, which

are vertically adjustable by screwing them in or out.

A beam 38, which is at least as long as the path along which vehicle 1 travels, is attached on the side of vehicle 1 to vertical support members 8a and 9a. A roller chain 39 is attached to the ends of beam 38 and extends along the length thereof. A sprocket 40, which is mounted on the drive shaft of a reversible electric motor 41, engages roller chain 39. A switch is located at either end of the path of vehicle 1. Each time one of the switches is actuated, the direction of rotation of sprocket 40 changes. One of the switches, designated 42 in FIG. 1, is actuated when a member 43, which is pivotable about a horizontal axis, is tripped by arm 11. Switch 42 is connected to motor 41 by a pair of leads 44. Similarly, the other switch which is not represented in the drawing is actuated by a pivotable member which is tripped by arm 10 as vehicle 1 reaches the other end of its path of travel. The other switch is connected to motor 41 by a pair of leads 45.

After platform 20 is lowered onto boat fender 35, motor 41 is energized. As vehicle 1 reaches the end of the path of travel, the corresponding switch is actuated and motor 41 is reversed. Thus, vehicle 1 travels to the other end of its path, at which point, the corresponding switch is actuated to reverse motor 41 once again. Vehicle 1 continues to ride back and forth on rails 2a and 2b between the two ends of the path until motor 41 is deenergized. During this time, boat fender 35 rolls along the ground under platform 20. As boat fender 35 rolls, the radius of the cylinder, along which the downward force is exerted, continually changes and with it the direction of deformation of boat fender 35 also changes.

After the radial strength of the boat fender is tested and motor 41 is deenergized, fender 35 remains under platform 20 while its axial strength is tested by pulling on one of the fixtures.

What is claimed is:

1. Apparatus for testing the strength of boat fenders comprising: a vehicle; means for restraining the vehicle to move along a substantially straight path; means for transporting the vehicle back and forth between two points on the straight path; and means on the vehicle for exerting a downward force on a boat fender resting on the surface along which the vehicle moves while the vehicle is being transported, the force beam applied to compress the fender while the vehicle moves back and forth so as to stress the fender while it is rolling and to simulate the forces in actual use of the fender.

2. The apparatus of claim 1, in which the restraining means are rails and the vehicle has wheels that engage the rails.

3. The apparatus of claim 1, in which the means for exerting a downward force is retractable out of contact with a boat fender resting on the surface along which the vehicle moves.

4. The apparatus of claim 1, in which the means for exerting a downward force is a horizontal platform.

5. The apparatus of claim 4, in which the horizontal platform is attached to the movable arms of cylinders which are fixed with respect to the vehicle such that the platform is retractable away from the surface along which the vehicle moves.

10 6. The apparatus of claim 1, in which the means for exerting a downward force exerts an adjustable downward force on a fender resting on the surface.

7. The apparatus of claim 5, in which adjustable stops are provided to limit the downward movement of the platform, thereby controlling the amount of force applied to the fender.

8. The apparatus of claim 1, in which the vehicle has vertical support members and the platform has guide means for maintaining its lateral position relative to the vertical support members.

25 9. The apparatus of claim 1, in which the means for moving the vehicle back and forth comprises a reversible motor that is controlled by switches located at either end of the path of the vehicle, the switches being actuated by means located on the vehicle as the vehicle approaches the end of the path.

10 10. The apparatus of claim 9, in which a roller chain is mounted to the vehicle and extends along its length a distance at least as long as the path of travel of the vehicle and a sprocket driven by the motor engages the roller chain.
